UNITED STATES PATENT OFFICE.

ALFRED RORDAME, OF SALT LAKE CITY, UTAH.

DRY-CELL BATTERY.

1,080,234.

Specification of Letters Patent.

Patented Dec. 2, 1913.

Application filed May 14, 1913. Serial No. 767,740.

To all whom it may concern:

Be it known that I, ALFRED RORDAME, a citizen of the United States, residing at Salt Lake City, in the county of Salt Lake 5 and State of Utah, have invented certain new and useful Improvements in Dry-Cell Batteries, of which the following is a specification.

My invention relates to dry cells for generating electric current, and has for its object to provide a dry cell which will prevent the escaping of the energizing paste thereof from between the bibulous lining and the container and hold the said energizing paste 10 in place when the chemical changes occur, which changes must take place when electricity is thus generated, and will prevent said paste from escaping over the sides of the container, the forming of short circuits 15 and the rapid deterioration of the cell. These objects I accomplish with the device illustrated in the accompanying drawings in which similar letters of reference indicate like parts throughout the several figures, 20 and as described in the specification forming a part of this application and pointed out in the appended claims.

In said drawings Figure 1 is an elevation of one of my cells, with parts cut away, and 25 parts shown in vertical section. Fig. 2 is a plan view of a portion of the screen packing.

In dry cells as usually constructed the energizing paste is often forced from between the bibulous lining and the metal container, 30 by certain gases which are liberated by the chemical action generating the electric current, and in most cases said paste will be thus forced, by said gases, between the sealing means and the container and will flow 35 over the sides of said container and soak into the insulating jacket around the cell and establish an external short circuit when said saturated jacket comes in contact with other saturated jackets of adjacent cells, similarly 40 constructed and likewise affected. In this way a number of adjacent cells will be quickly ruined.

My invention consists more specifically in 45 interposing between the metal container and the bibulous lining, an insulated screen packing, having interstices obliquely disposed therein. In this way the bibulous lining is held a short distance from the metal container and the energizing paste is forced

to fill said space in said interstices and 55 around said screen packing. The purpose of so spacing the bibulous lining and metal container apart, by a non-collapsible element, such as my screen packing, is, that when the chemical changes occur and gases 60 are generated, the bibulous lining will not thereby be forced toward the interior wall of the metal container and force the energizing paste upward and out of the container and will at the same time provide free contact of said energizing paste with said metal 65 container.

Referring now to the drawings: the container 1, is made of zinc preferably as a cylindrical cup with open top. A screen pack- 70 ing made of two or more telescoped cylinders 8 and 9, constructed of coarse mesh screen material, made of cotton netting, which has been dipped into plastic celluloid, rubber or other insulating material, is placed 75 within said container, with the interstices obliquely disposed and filled with the energizing paste 10. A simple and convenient method of making said cylinders and placing them in position to form the pack- 80 ing is to construct the cylinders of coarse cotton netting and dip them into the insulating and stiffening paste, and when said paste is dried, to telescope one within the other and move one on their common axis, 85 so that the openings or interstices in the walls of one cylinder will not be in alignment with those of the other cylinder, to form a rigid noncompressible packing having a great many openings in and through 90 its wall. The usual bibulous lining 2 is then inserted with a portion thereof upstanding above the walls of the container. The usual carbon electrode 4 is centrally placed in said container 1 and the depolarizing battery 95 mixture 3 is tightly packed around said electrode 4 filling the said container to near the top. The bibulous lining 2 is turned over on top of the battery mixture. The usual absorbent 6 and sealing mixture 5 are then 100 put in place to fill said container. The insulating jacket or outer covering 7 is secured on and around said metal container. As will be obvious the pressure of the generated 105 gases on the bibulous lining can not force the energizing paste out of the space between said lining and container and any tendency to move said paste upward will be prevented.

by the screen packing; and the paste will be held in place during the whole life of the cell.

Having thus described my invention I desire to secure by Letters Patent and claim:—

- 5 1. A dry battery comprising a zinc container; a packing therein composed of coarse mesh insulated screen cylinders with the interstices in staggered relation and filled with energizing paste; a bibulous lining within the inner of said screens; a centrally disposed electrode; a battery mixture between the electrode and said bibulous lining; and a seal for said container.
- 10 15 2. A dry cell battery comprising a zinc

container; a plurality of coarse mesh cotton netting cylinders one within the other with the interstices out of radial alignment; an energizing paste in the interstices of said netting; a cylindrically shaped bibulous lining within the inner of said cylinders; a centrally placed electrode; a battery mix between said electrode and said bibulous lining; and a sealing means for said container.

In testimony whereof I have affixed my signature in presence of two witnesses.

ALFRED RORDAME.
